UNITED STATES PATENT OFFICE.

HENRY D. HINCKLEY, OF HARTFORD, CONNECTICUT, ASSIGNOR TO JOHN B. HART, OF HARTFORD, CONNECTICUT.

SWITCH.

1,052,920.

Specification of Letters Patent.

Patented Feb. 11, 1913.

Application filed October 14, 1911. Serial No. 654,623.

To all whom it may concern:

Be it known that I, HENRY D. HINCKLEY, a citizen of the United States, residing at Hartford, in the county of Hartford and 5 State of Connecticut, have invented certain new and useful Improvements in Switches, of which the following is a specification.

This invention relates to switches, one of the primary objects of the invention being to 10 provide an effective and safe article of this character by which the switch proper or circuit controlling member can be moved with rapidity and positively from a circuit-closing position to thereby prevent arcing, such 15 movement being preferably in a straight line.

Another object is the provision of means whereby the switch mechanism can be readily mounted upon or removed from a 20 back board or equivalent.

The device includes several other features of novelty and advantage which with the foregoing will be set forth at length in the following description wherein I will outline in detail that form of embodiment of the invention, which I have selected for illustration in the drawings accompanying and forming part of the present specification. From the statement just made it will 25 be clear that I do not restrict myself to such showing. I may depart therefrom in several respects within the scope of the invention included in the claim following said description.

30 Referring to said drawings: Figure 1 is a transverse sectional view of a switch involving my invention. Fig. 2 is a vertical section, and, Fig. 3 is a horizontal section of the same.

40 Like characters refer to like parts throughout the several figures of the drawings.

The switch mechanism, as it might be considered, involves in its make-up a suitable 45 carrier 5 which may be made of any suitable material but which usually consists of a block or sheet of insulating material such as fiber, porcelain or the like. The switch proper, as will hereinafter appear, is directly supported by this carrier or body 5. In the present instance this carrier is removably connected in some convenient manner as by screws or bolts 5' with a suitable back piece which may be of any suitable nature but which as shown consists of the bottom or

rear section of a box or casing as 6, provided with a drop front 7, said box being generally made of metal; it may, for instance, be made by casting, although this is not essential. The drop front is hinged or otherwise suitably fastened to the upper wall of the box or casing 6 and is normally held shut by a spring catch 8 or some equivalent device. Within the box 6 I have represented several bosses or hubs as 9, there being four such bosses 60 or hubs. Threaded into said bosses or hubs 9 are bushings as 10 which are usually made of some insulating material such for example as fiber. Threaded or otherwise suitably fitted into the bushings 10 are 65 socket pieces as 11 constituting terminals and which are preferably but not necessarily made of metal, and these socket pieces 11 are adapted in the construction shown, to receive coöperating terminals as studs 12 70 projecting rearward from and through the carrier 5 of the switch mechanism, being generally rigidly connected to said carrier. The fit between the studs 12 and socket pieces is a tapered one so as to insure a solid, 75 firm relation therebetween. On the upper and lower walls of the box 6 are shown hubs or bosses 13 which are customarily but not necessarily made integral with said box and into these bosses 13 may be fitted the conduits ordinarily found in buildings for housing and carrying wires such as 14. These wires 14 can be, as will be clear, led into and from the box or casing 6 by way of said bosses 13, and can be connected with the 80 socket pieces 11 the lower wires, as will be clear, being connected to the lower socket pieces, while the upper wires are likewise connected to the upper socket pieces, by first baring the wires near their inner ends 85 and then wrapping or coiling the bared portions about the shanks of said socket pieces, the heads of said socket pieces being adapted to press the coiled portion of the wires firmly against the bushings 10 or against a 90 washer thereon. There will be when the switch mechanism is dismounted, a break between the two sets of socket or contact members 11, and when the switch mechanism is in place, as will hereinafter appear, the switch member proper or circuit controller when in circuit closing position, will 95 bridge the breaks thereby to put the two sets of wires leading into and out of the casing 6 into electrical connection. It will 100 105 110

be assumed that there is some trouble with the switch mechanism, and in this case it may as a unit be removed for repair. In such an event two conductor members can be utilized to bridge the breaks between the two sets of contacts or socket pieces 11, said conductors, of course, having pins or something equivalent to be thrust into the respective contact members 11, so that it is not necessary to shut down the system in its entirety to make repairs in the switch.

It is not essential that the back plate consist of the bottom of the box 6. The said box or its equivalent will be installed in a building as a permanent part thereof, during the construction of the building so that when it is necessary the switch can be mounted in place by simply inserting the posts or studs 12 in the appropriate socket pieces 11.

The switch proper or circuit opening and closing member is preferably in the form of an insulating block or strip 15 having a straight movement during circuit opening and closing positions. Such a form of switch is very effective in that rapidity of action is assured during the circuit breaking movement, so that possibility of arcing is reduced to the minimum. In the construction shown said switch or circuit controlling member 15 is perforated at or near its opposite ends to receive and slide upon the fixed guide rods or studs 16 generally arranged in parallelism provided with the buffers 16' and as shown extending outwardly from the carrier 5 and held in place thereon by screws 17 countersunk in the rear surface of said carrier. Encircling the two guide members 16 are coiled push-springs 18, the inner ends of which engage the carrier 5, while the outer ends thereof engage the circuit controlling member 15. In Fig. 3 the circuit controlling member 15 is shown in its circuit opening position into which it was moved by the springs 18. To close the circuit as will hereinafter appear, said circuit controlling member is thrust inward and on such action the springs 18 are compressed. When the circuit controlling member 15 is in said circuit closing position, it is positively held therein and a suitable detent or latch is provided for this purpose. When the latch is tripped, the springs are adapted to instantaneously throw said member 15 in an outward direction, so that the circuit will be so rapidly broken as to effectually prevent arcing.

The carrier is shown provided with binding posts 19 to which the outwardly extending clips or contact members 20 are connected, and with a substantially similar pair of contact members or clips 21, the several clips being adapted to receive between their resilient branches the parallel knife members 22 rigidly fastened to the inner side of the circuit controlling member or switch proper 15.

The binding posts 19 are connected by wires as 23 with the lower pair of pins or terminals 12, while the upper clips 21 are connected by wires as 24 with the upper pair of terminals or pins 12, the several binding posts 70 or pins 12 extending through the carrier 5 for this purpose. The wires 23 are placed in channels 23' in the back of the carrier which channels are adapted to be filled with wax, cement or other suitable insulating substance 75 to cover said wires 23. It will, therefore, be clear that when the controlling member 15 or bridging parts 22 fit between the branches of the several clips 20 and 21, the wires 14 leading into and out of box or casing are 80 thus put into electrical connection when the switch mechanism is in operative relation.

As previously intimated the circuit controlling member 15 is positively held in its circuit-closing position and to obtain this result a latch as 25 may be provided and as will hereinafter appear said latch may be tripped manually or electrically or in fact in any other desirable way. As shown the latch 25 is pivoted at its butt or inner end to the carrier 5. Fastened to and depending from the controlling member 15 is a plate 26 which has in its lower or free edge the slot or notch 27 to receive the bent portion of the latch 25, said latch being provided with a stop portion or shoulder 28 to engage the upper wall of said slot or notch 27 when the controlling member 15 is in its circuit closing position, and as will hereinafter appear the latch 25 is positively moved, as by a spring, to its operative or effective position. It will be assumed that the circuit controlling member 15 is thrust inward until such point as the detent portion 28 of the latch can engage the catch portion of the keeper plate 26 at which 105 time said detent portion will by the spring hereinafter described be thrust in front of said keeper plate to hold the part 15 in circuit-closing position until such time as the latch 25 is tripped.

On a shelf or bracket fastened to the carrier 5 is supported an electro-magnet 29 wired to a battery (not shown). When the battery circuit is closed the magnet 29 will be energized to attract its armature 30 carried by the arm 31 pivoted upon the shank of the lever 25. To a hook on said pivoted member or arm 31 is connected one end of a spring 32, the other end of said spring being fastened in the top of the box 33. 115 This box 33 in addition to incasing the spring 32 also serves as a buffer for receiving the shocks of the circuit controlling member 15 when the same is pushed inward. It will be assumed that the circuit controller 15 is 125 thrust rearward until the catch or keeper plate 26 is engaged by the latch 25. It will be assumed that necessity arises for breaking the high tensioned circuit controlled by the member 15. In this event the magnet 130

29 is energized by closing the battery circuit, which thereby attracts its armature 30 and consequently trips the latch 25. The instant said latch is tripped, the keeper 5 plate 26 is released as is the controlling member 15, by reason of which the springs 18 can instantaneously thrust the circuit controlling member 15 outward to break the main circuit. The electro-magnet 29 is 10 shown inclosed by the box 34 of insulating material, the sides of which are extended upward between the guide members or rods 16, so that the said box in addition to serving to incase the electro-magnet 29 also acts 15 as an insulating means. The free end of the lever 25 is provided with a removable finger piece 35 preferably of some suitable insulating material. The lever 25 can, therefore, be tripped at any time by hand. To move the circuit controlling member 15 rearward, the knob 36 may be provided, said knob preferably but not necessarily being made of insulating material and being fastened to the pin or stud 37 which extends through a slot in the out face plate 7 and is tapped into the circuit controlling member 15. The stud 37 can, therefore, be removed, and when it is, it is not possible to operate the member 15 when the box 6 is closed.

A switch involving my invention can be used with advantage in any connection where such articles are ordinarily employed, although said switch is of especial utility when employed in connection with an engine stop or such like life saving appliance where rapidity of action is a necessary factor. It is conceivable that the latch to which I have already referred might be tripped at all times by hand to effect the release of the circuit controlling member. I prefer in addition to this manual control to provide for electrical government, and when the switch is used in combination with an 15 engine stop or something equivalent I will arrange in a factory on each floor a large number of push buttons or equivalent means

for closing the local or battery circuit to thus energize the battery and thereby effect electrically tripping of said latch. Another 50 point to which I might call attention is the safety of the switch, all parts being insulated and properly protected, and some of them in fact serving double functions. The mounting of the construction is also an 55 important consideration, in that when it becomes necessary to connect the carrier no wiring is necessary, everything being already wired. The only point required for the individual who puts the carrier 5 or its 60 equivalent in place is to see that the terminals on the rear of said carrier are properly introduced into the appropriate socket pieces or some other like connection made so as to put the parts on the carrier into 65 electrical connection with those on the back of the box 6 or analogous part.

What I claim is:

A switch comprising a casing, a pair of parallel, rigid guide rods in the casing, an 70 insulating block supported by said guide rods for back and forth movement, spring means acting against the block to constantly move the same in an outward direction, two pairs of clips in said casing, blades connect- 75 ed with said block and adapted to enter between said clips when the block is in its inner position, a shank connected with said block and provided with a knob at its outer end, the casing having an opening through 80 which said shank extends, a latch mounted in the casing, the latter having an opening through which the latch extends, and said block being provided with a detent engageable by the latch to thereby hold the block 85 in its inner position, and an electromagnet, the armature of which is supported by said latch.

In testimony whereof I affix my signature in presence of two witnesses.

HENRY D. HINCKLEY.
